Inventor
George W. Smoot

UNITED STATES PATENT OFFICE.

GEORGE W. SMOOT, OF WASHINGTON, DISTRICT OF COLUMBIA, ASSIGNOR
OF ONE-HALF TO JOHN H. D. NORDEMAN, OF SAME PLACE.

TOBACCO-PIPE.

SPECIFICATION forming part of Letters Patent No. 295,066, dated March 11, 1884.

Application filed October 5, 1883. (No model.)

To all whom it may concern:

Be it known that I, GEORGE W. SMOOT, a citizen of the United States, residing at Washington, in the District of Columbia, have invented certain new and useful Improvements 5 in Tobacco-Pipes; and I do hereby declare the following to be a full, clear, and exact description of the invention, such as will enable others skilled in the art to which it appertains to 10 make and use the same.

This invention relates to certain new and useful improvements in pipes for smoking tobacco; and it consists in the peculiar construction and arrangement of the parts, as will 15 be hereinafter fully explained and specifically claimed, reference being had to the drawings herewith filed as part hereof, and in which similar letters of reference relate to the same parts.

20 Figure 1 is a side elevation of my improvement, showing the detachable bottom piece partially unscrewed from the body of the pipe. Fig. 2 is a transverse section, more fully illustrating the construction thereof. Fig. 3 is a side elevation, partly in section, 25 and showing a modification in the outside finish of the detachable piece completing the bowl of the pipe. Fig. 4 is a top view of the bottom piece with the outside finish, as shown 30 in Fig. 1.

A is the bowl, the lower part of which is provided with a reduced and screw-threaded extension, as shown at a'' , below the stem E E'. Said screw-thread must be cut on the 35 outside of said reduced extension a'' , in order to protect the thread from becoming fouled and disabled by the usual deposit of nicotine while in use, and also burning tobacco, should the charge be allowed to burn to a low state.

40 C is a removable piece, which is provided with a recess and screw-thread corresponding with the thread on the extension a'' , and completes the body and bowl of the pipe by being screwed thereto, as shown in Figs. 1, 2, 3. The bottom piece, C, is ribbed, as shown 45 at e' , Figs. 1 and 4, or check-grooved, as shown at e'' in Fig. 3, for the purpose of fa-

cilitating the removal and adjustment of the piece C by a firm hold thereon. For this purpose ribbing the outside of the piece C, 50 as shown at e' in Figs. 1 and 4, is preferable. The piece C may and should be so dimensioned that it may be attached to a templet provided with a screw-threaded projection corresponding to the threaded recess in said 55 piece, whereby the same may be attached to said templet, and thus be rapidly and economically finished to the proper size and provided with ribs, as shown. The piece C may also be affixed to a templet in the same 60 manner, and check-grooved, as shown at e'' , Fig. 4.

The chamber a' of the pipe may be provided with a lining of meerschaum or other suitable material, as shown and referred to by a'' in 65 Fig. 2. When the bowl is so lined, the lining should extend from the top of the pipe to the end of the screw-threaded extension a''' , with the edge of which it should have an even and smooth finish, in order that a perfect joint 70 may be formed with the corresponding part of the piece C, and thus prevent the nicotine or fire, as the case may be, from fouling or disabling the screw-threads by contact therewith. When the pipe is lined, the lining 75 should be perforated, as shown at e' , to correspond with the draft e of the stem E E', which may be made in two parts by screw-joint or otherwise, as indicated at e'' , Fig. 1, and more fully illustrated at e'' in Fig. 2. The bowl 80 should be also provided with a lid or cover, D, which may be secured from loss by chain d , connecting with the ring d' around the stem E. The lid D should have the usual perforations, to facilitate the draft and burning of the 85 charge.

The use of the within-described improved pipe may be continued without the necessity of relighting by removing the piece C and inverting the pipe, after which the remaining 90 portion of the charge containing the fire may be moved to the top of the bowl and the same conveniently recharged from the bottom.

Having thus explained the construction and

operation of my improvement, what I claim as new, and desire to secure by Letters Patent, is as follows:

The bowl A, provided at its lower end with 5 a contracted and externally-threaded portion, a'' , and having the lining a' , extending the whole length of its chamber, in combination with the recessed bottom piece, C, suitably

threaded to engage the threaded portion of the bowl, substantially as set forth. 10

In testimony whereof I have affixed my signature in presence of two witnesses.

GEORGE W. SMOOT.

Witnesses:

J. C. MILLER,

JOHN H. D. NORDEMAN.
